UNITED STATES PATENT OFFICE.

ANTON M. RASMUSSEN, OF ROCKFORD, ILLINOIS.

IRONING MACHINE.

Application filed June 4, 1926. Serial No. 113,598.

This invention relates to ironing machines of the mangle type.

One of the principal objects is to provide, in connection with an ironing roll in a machine of the type mentioned, a plurality of padded rolls for feeding the work in contact with the ironing roll, there being a provision for driving one of the feed rolls at a slower peripheral speed than the others to create a drawing effect on the material being ironed and produce a glossy finish.

Another important object is to provide a machine of the type mentioned having an electrically heated and driven ironing roll of an open end type, that is, supported and driven at only one end, thus affording a wider range of possible uses for the machine and making the entire area of the ironing surface available for use.

Still another important object of the invention is the provision of a guard which positively eliminates the danger of getting fingers caught between the rolls, the guard being arranged to control the electric circuit of the driving motor furnishing the power to turn the ironing roll so that the machine is thrown out of operation the instant there would otherwise be danger of the operator's fingers coming between the rolls, while the guard also affords a convenient means for starting and stopping the machine at the will of the operator without the necessity of using the starting switch. In addition to this safety feature, the invention provides a means hereinafter described for instantly releasing the feed rolls from operative relation to the ironing roll by the operation of a treadle within convenient reach at any point along the front of the machine.

The invention is described in more complete detail in the following specification, wherein reference is made to the accompanying drawings illustrating one embodiment in which—

Figure 1 is a front view of the machine;

Fig. 2 is an end view taken from the right hand end of Fig. 1;

Fig. 3 is a view taken from the opposite end of the machine;

Fig. 4 is a top view of Fig. 1; and

Fig. 5 is a longitudinal section through the ironing roll and the mounting thereof. The same reference numerals are applied to corresponding parts throughout the views.

The machine illustrated has a frame composed of end uprights 6 and 7 on a base 8 suitably braced by cross-members 9. An ironing roll 10 of the open end type is supported at only one end on the upright 6 in a manner illustrated in Fig. 5. This type of roll offers many advantages over the closed end type and makes it possible to iron pieces which would otherwise be too wide for the machine. While the construction and the mounting of the roll may be varied to a considerable extent, I have chosen to select for the purposes of illustration a mounting, as shown in Fig. 5, comprising a journal 11 received in a bearing 12 provided in the upright 6. The journal 6 constitutes a hub onto which the parts of the roll 10 are assembled. Thus an inner shell 13 of one or two pieces has a tapered bore to fit on the tapered end 14 of the journal 11 and thereby become centered with respect to the outer shell 15. The outer shell is supported on a ledge 16 provided on an end plate 17 which in turn is mounted on a ledge 18 on the journal 11. A cap 19 for the other end of the roll 10 is received in the countersunk end 20 of the outer shell 15 and has a tapered boss 21 to be received within the end of the inner shell 13, thus centering the shells 13 and 15 with respect to one another. A standard is provided in the form of a rod 22 threading at one end in the journal 11 and receiving a nut 23 at its other end to hold the parts in assembled condition. An annular coil chamber 24 is provided between the shells 13 and 15 for the heating units 25, there being suitable insulation therefor, as shown at 26. Lead-ins 27 for the heating units 25 extend to terminals 28 on the outside of the journal 11. The current for the heating units is supplied in the rotation of the roll 10 in a manner similar to that shown in my Patent No. 1,481,225, dated January 15, 1924. Briefly stated, I provide two conducting rings 29 and 30 each of which is associated with a separate trolley wheel 31 associated with one of the terminals 28. The conducting rings 29 and 30 are in turn associated with the wires 32 and 33 respectively leading to the source of electric current. The roll 10 is arranged to be driven by the turning of the journal 11 with a worm gear 34 preferably formed integral with the journal. The gear 34 meshes with a worm 35 on the armature shaft of a motor 36 supported on a bracket

37 mounted on the back of the upright 6, as shown in Fig. 3. The end plate 17 and the worm gear 34 together afford thrust bearings of ample radius with respect to the 5 journal 11 on opposite sides of the upright 6. It will be obvious that any suitable anti-friction bearing elements may be interposed in the journal bearing and in the thrust bearings if so desired. The lubrication of 10 these bearings is herein illustrated as accomplished through the oil ducts 38.

The ironing roll 10 has spur gear teeth 39 formed on the periphery of the outer shell 15 thereof adjacent the end plate 17, as shown in Fig. 5. A plurality of padded rolls 40, preferably three, are disposed about the ironing roll, as shown in Fig. 2, the first roll, designated A, being at the top of the roll 10 and the other two, designated B and 20 C, respectively being advanced approximately 45° and 90° with respect thereto around the back of the roll. Rolls B and C are provided with gears 41 on the end thereof meshing with the gear teeth 39 so that 25 these two rolls are driven at approximately the same peripheral speed as the ironing roll 10. A supporting frame 42 is provided for the three rolls and, as will presently appear, is arranged for movement to carry the 30 rolls simultaneously into or out of operative relation to the ironing roll. The roll designated B is provided with a spur gear 43 on the end thereof opposite the gear 41. The roll designated A carries a gear 44 which, it will be seen on comparison in Fig. 35 2, is approximately one and one-half times as large as the gear 43, the purpose being to provide a ratio of about two to three between the gears 43 and 44 so that when the 40 roll A is driven from the roll B by the meshing of the intermediate idler gear 45 with the gear 44, the roll A will be turned at a somewhat slower peripheral speed and thus create a drawing effect on the material being 45 ironed. The rolls B and C will thus be caused to slide relative to the work as they are turning at a faster peripheral speed than the lineal speed of the material. This, as is well known, will produce a glossy finish, 50 which is desired on certain kinds of work. The gear 45 is in constant mesh with the gear 43 and is arranged to be thrown into mesh with the gear 44 at the will of the operator as in the case of a shifttable back gear 55 on a lathe or the like. The gear 45 is, therefore, mounted on a shifttable hand lever 46 within convenient reach of the operator standing at the front of the machine. The lever 46 is preferably provided with a spring 60 pressed detent at 47 to engage in either one of two openings 48 provided on the side of the frame 42 to hold the gear 45 in or out of mesh with the gear 44. It will be obvious 65 that with the gear 45 out of mesh with the gear 44 the roll designated A will operate

idly with the ironing roll at about the same peripheral speed and the speed thereof will be retarded only when the gear 45 is shifted into mesh in the manner shown in Fig. 2.

The work is fed to the machine over a 70 table 49 at the front of the machine mounted on a bracket 50 supported on the upright 6. The work leaves the machine over a shelf 51 supported by brackets 52 on the uprights 6 and 7. The shelf 51 extends beneath the 75 ironing roll and has the inner end portion thereof curved upwardly around the back of the roll, as shown at 53, to provide a chute for guiding the work as it leaves the roll designated C forwardly over the shelf 51. 80 There is, therefore, no opportunity for the work to become fouled with any part of the machine. The table 49, as shown in Fig. 2, terminates in front of the point where the work enters between the ironing roll and the first padded roll designated A. A guard or shield 54 is pivotally mounted on the frame 42 at 55 and disposed across the entire front of the roll A so that the work has to pass beneath it into the machine. A lug 56 projects from the top of the guard 54 and carries a contact terminal 57 connected in series with the starting switch for the motor 36. A lug 58 projecting from the frame 42 bears another contact terminal 59 normally 95 engaging with the contact 57 to complete the circuit through the motor 36. The circuit is broken by pressure against the guard 54 against the action of coiled compression springs 60 disposed about a rod 61 and acting 100 between the rod and the lugs 56 and 58 to keep the contacts 57 and 59 normally closed. The guard, therefore, yields only under appreciable pressure such as might be occasioned by the operator unconsciously 105 moving his hands in too close to the rolls in smoothing out the work. The moment the guard is moved in the manner stated the machine is stopped. The guard, therefore, provides for the safety of the operator and 110 it is impossible to get his fingers near the danger zone without bringing the machine to a standstill. The guard may also be used as a convenient means for starting and stopping the machine without touching the starting switch. 115

Another safety feature is provided by enabling the operator to instantly release the padded rolls from operative relation to the ironing roll in the event anything becomes 120 caught between the rolls. A treadle 62 pivoted at 63 extends across the front of the machine to be within easy reach to the operator at any time. A link 64 joined to the treadle 62 is connected with the intermediate 125 pivot 65 of a pair of toggle links 66 and 67. The former is pivoted to a stationary part of the machine at 68. The link 67 has a pin and slot connection at 69 with a yoke 70 pivoted at 71 to a rocking lever 72. The 130

latter is arranged to oscillate a shaft 73 received in bearings provided on brackets 74 mounted on the uprights 6 and 7. A pair of arms 75 support the frame 42 and are arranged to rock with the lever 72 in the oscillation of the shaft. The link 67 is slideable within the yoke 70, as indicated in dotted lines in Fig. 2 to the extent permitted by the lost motion connection 69. A compression spring 76 acting between the yoke 70 and a shoulder on the link 67 yieldingly holds the parts in the relative position shown in Fig. 2. In the event any impediment is fed between the rolls as, for example, buckles or buttons and the like, the padded rolls are free to yield to the extent afforded by the lost motion connection 69. The spring 76, however, normally keeps the padded rolls in proper contact with the ironing roll. The padded rolls 40 with their supporting frame 42 overbalance a counter-balancing spring or springs 77 under the action of gravity to such an extent as to be held with a light pressure against the ironing roll. Due to the counter-balancing springs 77, only a very light foot pressure is required on the treadle 62 to elevate the padded rolls out of operative position. Furthermore, the counter-balancing springs hold the padded rolls in substantially floating relation to the ironing roll so that they will yield readily and prevent the breakage of buttons and avoid any possible jamming of the machine.

It is believed that the foregoing description affords a clear understanding of the invention as expressed in the objects prefaced above and while I have illustrated but a single embodiment, it should be understood that various changes might be made in details without sacrificing the more important advantages derived by the present construction. Such modifications are to be considered as embraced within the spirit and scope of the invention as expressed in the appended claims.

I claim:

1. In an ironing machine, an ironing roll, a plurality of rolls alongside the same serving to feed the work in contact therewith, certain of said rolls having a permanent drive connection with a power source to turn at about the same peripheral speed as the ironing roll, a remaining roll being normally arranged to operate at about the same peripheral speed as the ironing roll but having provision for a disengageable drive connection with the power source to be driven at a lower peripheral speed when desired.

2. In an ironing machine, an ironing roll, a plurality of feed rolls disposed alongside the same in advance of one another serving to feed the work in contact with the ironing roll, a gearing connection between the second to the last roll and said ironing roll for turning said roll at about the same peripheral

speed as the ironing roll, a gear for driving the last roll, a smaller gear turning with the second to the last roll, a shiftable idler gear to connect the two last mentioned gears, and a hand lever carrying said shiftable gear. 70

3. In a machine as set forth in claim 2, the provision of means for releasably holding the hand lever in adjusted position.

4. In an ironing machine, a rotating ironing roll, a work table over which work is fed to said roll, a first feed roll normally operating idly at about the same peripheral speed as the ironing roll to hold the work in contact therewith, a second feed roll in advance of the first feed roll, means to drive the latter always at the same peripheral speed as the ironing roll, and means for selectively driving the first roll at a slower speed. 80

5. In an ironing machine, an ironing roll, a plurality of feed rolls alongside the same normally operating substantially in contact therewith, a movable support for said feed rolls whereby the same may be removed together out of operative relation to said ironing roll, said rolls with said support tending normally to move toward said ironing roll under the action of gravity, counter-balancing spring means for said support and the rolls carried thereby arranged normally 95 to allow the rolls to assume their operative positions, and operator operated means arranged to supplement the force exerted by said counter-balancing means whereby to raise said rolls with their support out of 100 operative position.

6. In an ironing machine, an ironing roll, a plurality of feed rolls alongside the same normally operating substantially in contact therewith, a movable support for said feed rolls whereby the same may be removed together out of operative relation to said ironing roll, a rocking frame bearing said support on one side of its pivotal mounting arranged normally to rock one way by the 110 weight of said support and the rolls carried thereby to bring the rolls into operative position, operator operated means connected with said frame on the other side of its pivotal mounting to move said rolls with 115 their support out of operative position, and counter-balancing spring means connected with said rocking frame on the same side of the pivotal mounting thereof as said operator operated means serving normally to allow the rolls to move toward the ironing roll under light pressure. 120

7. In an ironing machine, an ironing roll, a plurality of feed rolls alongside the same normally operating substantially in contact 125 therewith, a movable support for said feed rolls whereby the same may be removed together out of operative relation to said ironing roll, a rocking frame bearing said support on one side of its pivotal mounting ar- 130

ranged normally to rock one way by the weight of said support and the rolls carried thereby to bring the rolls into operative position, and operator operated means connected with said frame on the other side of its pivotal mounting to move said rolls with their support out of operative position, comprising a pair of toggle links pivotally connected at one end to a stationary support and at the opposite end to said rocking frame, a treadle, and a link connection between said treadle and the intermediate pivot of said toggle.

8. In an ironing machine, an ironing roll, a plurality of feed rolls alongside the same normally operating substantially in contact therewith, a movable support for said feed rolls whereby the same may be removed together out of operative relation to said ironing roll, a rocking frame bearing said support on one side of its pivotal mounting arranged normally to rock one way by the weight of said support and the rolls carried thereby to bring the rolls into operative position, and means connected with said frame on the other side of its pivotal mount-

ing to move said rolls with their support out of operative position, comprising a pair of toggle links having pivotal connection at one end to a stationary support and having a lost motion pivotal connection at the other end with said rocking frame, spring means acting between the toggle link and said rocking frame normally taking up the lost motion at said pivotal connection, and an operator operated element having connection with the intermediate pivot of said toggle.

9. In an ironing machine the combination of a frame and an ironing roll having a journal portion at only one end thereof received in a bearing in said frame thereby leaving the other end of the roll free, bearing means at the supported end of the roll assuming the thrust against opposite sides of said frame adjacent the journal bearing, and gear teeth on the periphery of one of said last mentioned bearing elements for rotating the journal and with it the ironing roll carried thereby.

In witness of the foregoing I affix my signature.

ANTON M. RASMUSSEN.
